UNITED STATES PATENT OFFICE.

ALFONS OSTROWSKI, OF BERLIN, GERMANY, ASSIGNOR TO OSTROWSKI & CO., OF BERLIN, GERMANY.

LUNCHEON BOX AND THE LIKE.

Application filed March 21, 1923. Serial No. 626,473.

To all whom it may concern:

Be it known that I, ALFONS OSTROWSKI, a citizen of the German Republic, residing at 61 Markgrafenstr., Berlin, Germany, have invented certain new and useful Improvements in Luncheon Boxes and the like, of which the following is a specification.

This invention relates to sandwich, luncheon and the like boxes which are provided with separate compartments for the reception of food stuffs and of a bottle or flask, such as a thermos flask for example, and its main object is the provision of a box or canister of this kind which shall be more serviceable and convenient for its purpose than the hitherto known boxes of this class.

With this main object in view my invention mainly consists in a box, tin, canister or other receptacle, which is made of two parts and which is extensible so that it may be handled more conveniently. The container, according to this invention consists of a top and bottom portion, of which the latter serves to hold food stuffs, such as sandwiches for example, whereas the top portion is made as a sliding cover for the bottom portion and serves to hold a flask. Both parts can be fixed in two end positions relative to each other, namely the extended position when filled, and the contracted position after the food stuffs have been taken out. For this purpose my invention further consists in the provision of resilient means to quickly and effectively secure the two parts in their relative positions.

The accompanying drawings illustrate my invention by way of example:

Fig. 1 is a side elevation, and

Fig. 2 a front elevation of a sandwich box in its contracted position.

Fig. 3 is a side elevation, and

Fig. 4 a front elevation, partly in section, of the box extended;

Fig. 5 is an inside plan view of the cover,

Fig. 6 a cross section on line A—B of Fig. 5.

Fig. 7 shows a detail in section,

Fig. 8 is a cross section on line C—D of Fig. 2,

Fig. 9 is a longitudinal section on line E—F of Fig. 2, parts being broken away.

According to this drawing the sandwich box consists of a bottom compartment 1 and a top compartment 2 serving as a cover and

adapted to slide over compartment 1 in telescope-like manner, thereby almost completely enclosing same. The cover 2 is provided with eyelets 3 for attaching a handle or a strap. The end faces of the cover are provided with small leaf springs 4 which can be turned through a small angle about their longitudinal axes. The said leaf springs are held by tongues 5 bent up from the material of the box, with a certain amount of play, that is to say, the width of the springs is somewhat less than the distance between the bends of the tongues, so that there is sufficient space for the springs to be slightly turned (see Fig. 4). The leaf springs 4 are provided with pins 6 and 7, which project through holes 6' and 7' of the cover portion as illustrated in Fig. 8. When the box is in its collapsed position, the said pins 6 and 7 pass through holes 8 and 9, and in its extended position through holes 10 and 11, all provided in the face ends of the bottom part, thereby holding the two parts together (Figs. 3 and 4).

When the box is to be extended from the contracted position, the leaf springs 4 must first be grasped at their ends and the pins 6 and 7 pulled out from their corresponding holes 6' and 7' as well as from the holes 8 and 9, whereupon they are turned to a small degree (Fig. 4). The leaf springs are then pulled so that they are returned to their normal position, in which the pins again project through the holes 6' and 7' and thereby bear on the walls of the face ends of the bottom portion. The two parts of the box may be then pulled apart until the pins 6 and 7, on coming opposite the holes 10 and 11, are pressed into these holes by the pressure of their springs 4, thus locking the box in this extended position. It is preferable to arrange guide grooves, such as 12 in Fig. 4, in the face walls of the lower box, which facilitate the extension and collapsing of the device by guiding the pins into their respective holes. In order to separate the parts, the leaf springs 4 must again be turned and the pins 6 and 7 withdrawn from the holes 6' and 7', whereupon the top may be taken right off.

In order to enable an easy application of the cover and to automatically guide the pins 6 and 7 to the uppermost holes 10 and

11, the top edges 1' of the face walls of the lower compartment 1 are curved inwardly as shown in Fig. 9.

The lower compartment is intended for 5 the reception of food stuffs, for example sandwiches, and the top for the reception of a flask. For this purpose a hoop-shaped spring 14 is provided (see Fig. 6), which is also fixed by tongues 5 stamped and bent up 10 from the material of the box as indicated in Fig. 7. The flask, for example a thermos flask, is placed between the arms of the spring 14 and is locked in position by a strap 15 hinged to one end of the spring 15 and, at its other end, provided with a hook 16 which is passed through a corresponding slot in the other end of the spring. This way of fixing the flask ensures a proper hold and, at the same time, renders the removal of the flask very easy.

Ventilation holes (not shown) may be provided both in the lower and in the upper portions of the box and, if desired, additional holes, similar to 8 and 9, for the 25 reception of the pins 6 and 7 may be provided in the face walls of the bottom part, so as to enable an intermediate position of the parts between the two end positions above referred to.

30 A particular advantage of the new container is that it is possible to form the various parts, namely the top and bottom portions, the leaf springs for the locking pins and the spring hoop for the thermos 35 flask by stamping, thus reducing the cost of production to a minimum. The device is both serviceable and efficient.

What I claim is:-

1. An extensible luncheon box and the 40 like comprising a bottom compartment, a top compartment slidably connected thereto, the end walls of the bottom compartment having a plurality of pairs of holes therein, a leaf spring located on each end 45 wall of the top compartment, each end of the said springs having a pin adapted to project through an adjacent hole of the said end wall of said top compartment, said pins being adapted to project into the said holes in the bottom compartment.

2. An extensible luncheon box and the 55 like comprising a bottom compartment, a top compartment slidably connected thereto, the end walls of the bottom compartment having a plurality of pairs of holes therein, a leaf spring turnably connected to each end wall of the top compartment, each end of the said springs having a pin adapted to project through adjacent holes in the said end wall of said top compartment, said pins being adapted to project through said holes in the bottom compartment.

60 3. An extensible luncheon box and the 65 like, comprising a bottom compartment, a

top compartment slidably connected thereto, said top compartment having means adapted to hold a flask, bent-up tongues stamped out in pairs from the end walls of said top compartment, leaf springs turnably 70 connected to said top compartment, each spring being located between a pair of tongues with a small amount of free play, each end of each said spring having a pin 75 adapted to project through holes in the end wall of the top compartment, the end walls of the bottom compartments having holes adapted to receive the said pins.

4. An extensible luncheon box and the like comprising a bottom compartment, a 80 top compartment slidably connected thereto, means adapted to hold a flask in said top compartment, a leaf spring connected to each end wall of said top compartment, each end of the said springs having a pin adapted 85 to project inwardly through the said end walls of said top compartment, the lower parts of the end walls of the bottom compartment and the upper parts of the said end walls each having a pair of holes adapted 90 to receive the pins,

5. An extensible luncheon box and the like comprising a bottom compartment, a top compartment slidably connected thereto, means adapted to hold a flask in said top compartment, a leaf spring connected to each end wall of said top compartment, each end of the said springs having a pin adapted to project inwardly through the said end walls, the lower parts of the end 100 walls of the bottom compartment and the upper part of each end wall each having a pair of holes adapted to receive the pins, and also having grooves adapted to guide the pins from the said lower holes to the 105 said upper holes.

6. An extensible luncheon box and the like comprising a bottom compartment, a top compartment slidably connected thereto and adapted to act as a cover, a hoop-shaped spring located in said cover and adapted to hold a flask, a clip hinged to one end of said spring and adapted to lock the flask in position, said clip having a hooked end coating with a slot in the free end of the spring, and resilient means adapted to hold the said bottom and top compartments in a plurality of relative positions.

7. An extensible luncheon box and the like comprising a bottom compartment, a top compartment slidably connected thereto, resilient means including spring controlled pins adapted to hold the said compartments in a plurality of relative positions, the end walls of the lower compartment having holes adapted to receive said pins, said end walls having inwardly curved top edges to guide the pins when applying the top compartment to the lower compartment.

8. An extensible luncheon box and the like comprising a bottom compartment, a top compartment slidably connected thereto, resilient means adapted to suspend a flask and located in said top compartment, and resilient means adapted to hold the said compartments in both extended and contracted condition, said resilient means being attached to the said compartments by bent-over tongues stamped out from the material of the compartment walls. ¹⁰

In witness whereof I affix my signature.

ALFONS OSTROWSKI.
